UNITED STATES PATENT OFFICE.

ROY S. SANFORD, OF SOUTH BEND, INDIANA, ASSIGNOR TO BENDIX BRAKE COMPANY,
OF CHICAGO, ILLINOIS, A CORPORATION OF ILLINOIS.

BRAKE.

Application filed April 7, 1926. Serial No. 100,287.

This invention relates to brakes, and is illustrated as embodied in an internal expanding automobile brake. An object of the invention is to provide a simple brake of the 5 "servo" type in which all of the shoes are fully effective in either direction of rotation of the brake drum.

In one desirable arrangement there are 10 two pairs of shoes: a pair of main shoes, preferably arranged to anchor at their opposite ends when the drum is turning in opposite directions, and a pair of floating "servo" shoes, each arranged to force one of the main shoes against the drum. Important features of novelty relate to the 15 arrangement of the anchoring abutments, shoe-positioning stops, etc., to secure the maximum effectiveness of the shoes.

The above and other objects and features 20 of the invention will be apparent from the following description of one illustrative embodiment shown in the accompanying drawings, in which:

The figure is a vertical section through the 25 brake, just inside the head of the drum, showing the shoes in outside elevation.

The brake, in the form illustrated, includes 30 a rotatable drum 10, having at its open side a suitable stationary support or backing plate 12. On the backing plate are arranged the anchoring abutments for the shoes, four abutments 14, 16, 18, and 20 being shown.

On opposite sides of the drum are arranged 35 a pair of main brake shoes 22 and 24. When the brake is applied with the drum turning clockwise, shoe 22 anchors on abutment 16 and shoe 24 on abutment 20; when the drum is turning counterclockwise, shoe 22 anchors on abutment 14 and shoe 24 on 40 abutment 18.

Between the ends of the main shoes, and 45 therefore acting on the same zone of the drum, are servo shoes 26 and 28. At each end of each servo shoe is a part 30, which is projectable past the corresponding abutment to engage one or the other of the main shoes. When the drum is turning clockwise, servo shoe 26 forces shoe 22 against the drum and against abutment 16, while servo shoe 50 28 forces shoe 24 against the drum and against abutment 20. When the drum is turning counter-clockwise, servo shoe 26 forces shoe 24 against the drum and against abutment 18, while servo shoe 28 forces shoe 55 22 against the drum and against abutment 14.

The servo shoes are forced apart against the drum to apply the brake by means such as linkage including a double lever 32 on a shaft 34 floating in a slot 36 in the backing plate. At its upper end lever 32 is pivotally connected to shoe 26; at its lower end it is pivotally connected to a thrust link 38 which in turn is pivoted to shoe 28. Turning shaft 34 counter-clockwise thus forces both shoes against the drum.

The shoes are all urged away from the drum by return springs 40, against suitable stops 42. Each stop may be arranged opposite one of the four abutments, so that it is engaged by the adjacent ends of two of the shoes.

While one illustrative embodiment has been described in detail, it is not my intention to limit the scope of the invention to that particular embodiment, or otherwise than by the terms of the appended claims.

I claim:

1. A brake comprising, in combination, a drum, a pair of servo shoes engageable with opposite sides of the drum, and an additional plurality of shoes, part forced against the drum by one servo shoe and part by the other and anchoring at opposite ends when the drum is turning in opposite directions.

2. A brake comprising, in combination, a drum, a pair of servo shoes engageable with opposite sides of the drum, and an additional plurality of shoes, part forced against the drum by one servo shoe and part by the other, the part forced against the drum by each one of the servo shoes when the drum is turning in one direction being forced against the drum by the other of the servo shoes when the drum is turning in the opposite direction.

3. A brake comprising, in combination, a drum, a pair of servo shoes engageable with opposite sides of the drum, and an additional plurality of floating shoes each anchoring at one end when the drum is turning in one direction and at the other end when the drum is turning in the other direction, and part forced against the drum by one servo shoe and part by the other.

4. A brake comprising, in combination, a drum, a pair of servo shoes engageable with opposite sides of the drum, and an additional plurality of floating shoes each anchoring at one end when the drum is turning in one direction and at the other end

- when the drum is turning in the other direction, and part forced against the drum by one servo shoe and part by the other, the part forced against the drum by each one 5 of the servo shoes when the drum is turning in one direction being forced against the drum by the other of the servo shoes when the drum is turning in the opposite direction.
- 10 5. A brake comprising, in combination, a drum, a pair of main shoes engageable with the drum, a pair of servo shoes engageable with the drum, and means for forcing the servo shoes in opposite directions against 15 opposite sides of the drum and for causing each servo shoe to force one of the main shoes against the drum, the servo shoes being arranged between opposite ends of the main shoes.
- 20 6. A brake comprising, in combination, a drum, a pair of floating main shoes engageable with the drum and anchoring at either end, a pair of servo shoes engageable with the drum, and means for forcing the 25 servo shoes in opposite directions against opposite sides of the drum and for causing each servo shoe to force one of the main shoes against the drum when the drum is turning in one direction and the other main 30 shoe against the drum when the drum is turning in the opposite direction.
7. A brake comprising, in combination, a drum, main and servo shoes all disconnected from each other and all engageable 35 with the same zone of the drum, and means for forcing the servo shoes against the drum and permitting them to move with the drum to apply the main shoes.
8. A brake comprising, in combination, a 40 drum, main and servo shoes all disconnected from each other and all engageable with the same zone of the drum, and means for forcing the servo shoes in opposite directions against diametrically-opposite portions of 45 the drum and permitting them to move with the drum to apply the main shoes.
9. A brake comprising, in combination, a 50 drum, a plurality of abutments spaced about the drum, main shoes between the abutments and arranged to anchor thereon at their opposite ends when the drum is turning in opposite directions, and servo shoes 55 engageable with the drum and each of which forces one of the main shoes against the drum.
10. A brake comprising, in combination, a 60 drum, a plurality of abutments spaced about the drum, main shoes between the abutments and arranged to anchor thereon at their opposite ends when the drum is turning in opposite directions, and servo shoes 65 engageable with the drum and each of which forces one of the main shoes against the drum when the drum is turning in one direction and the other of the main shoes
- against the drum when the drum is turning in the other direction.
11. A brake comprising, in combination a drum, a plurality of abutments spaced about the drum, main shoes between the 70 abutments and arranged to anchor thereon at their opposite ends when the drum is turning in opposite directions, and servo shoes engageable with the same zone of the surface of the drum as the main shoes, and 75 each of which forces one of the main shoes against the drum.
12. A brake comprising, in combination, a drum, at least one main floating shoe within the drum, an abutment at each end of 80 the main shoe on which said shoe may anchor, and a pair of servo shoes at opposite ends of the main shoe and disconnected therefrom and each of which forces the main shoe against the drum when it anchors 85 against the abutment at the opposite end.
13. A brake comprising, in combination, a drum, friction means within the drum, four fixed anchoring abutments on at least 90 part of which said means anchors when the brake is applied, and a servo shoe between two of the abutments having at each end a part projectable past the corresponding abutment to apply the friction means without 95 engagement of the servo shoe with said abutment.
14. A brake comprising, in combination, a drum, friction means within the drum, four fixed anchoring abutments on at least 100 part of which said means anchors when the brake is applied, a servo shoe between two of the abutments having at each end a part projectable past the corresponding abutment to apply the friction means without engagement of the servo shoe with said abutment, 105 and a stop opposite each of said two abutments and on which the adjacent ends of the servo shoe and the friction means rest when the brake is not applied.
15. A brake comprising, in combination, 110 a drum, two pairs of abutments within the drum, a pair of main shoes, one between each pair of abutments, a pair of servo shoes arranged to force the main shoes against the drum, and a stop opposite each abutment, 115 each stop supporting in idle position the adjacent ends of two of the shoes.
16. A brake comprising, in combination, a drum, two pairs of abutments within the drum, a pair of main shoes, one between 120 each pair of abutments, a pair of servo shoes arranged to force the main shoes against the drum, a stop opposite each abutment, each stop supporting in idle position the adjacent ends of two of the shoes, and a 125 spring acting on each shoe and urging it against two of the stops.
17. A brake comprising, in combination, a drum, a pair of servo shoes engageable 130 with diametrically opposite sides of the

drum, means connecting the servo shoes and operable to force them apart against the drum, and a pair of main shoes, each arranged to be forced against the drum by one of the servo shoes.

18. A brake comprising, in combination, a drum, a pair of servo shoes engageable with diametrically opposite sides of the

drum, a linkage connecting the servo shoes and operable to force them apart against the drum, and a pair of main shoes, each arranged to be forced against the drum by one of the servo shoes.

In testimony whereof, I have hereunto signed my name.

ROY S. SANFORD.
